ROTARY MACHINE AND BUSHING
THEREFORWilliam D. Davidson, Los Angeles, Calif., assign-
or to Emsco Derrick & Equipment Company,
Los Angeles, Calif., a corporation of California

Application September 6, 1938, Serial No. 228,585

7 Claims. (Cl. 255—23)

My invention relates to improvements in rotary machines of the class commonly employed in the drilling of oil wells.

In the drilling of an oil well by the rotary method it is the practice to employ a drill pipe which extends into the hole and which has a bit secured to the lower end thereof. The upper end of the drill pipe is provided with a drive stem or kelly which is usually of rectangular cross-
10 section, which kelly extends through the table of the rotary machine which is supported on the derrick floor. For the purpose of rotatably driving the kelly it is the practice to provide a drive bushing or kelly bushing which is placed in the opening of the table of the rotary machine, which drive bushing has an opening of a cross-sectional shape corresponding to that of the kelly, and through which the kelly extends. When stands of pipe are being connected to or disconnected
20 from the string of drill pipe slips are employed which are supported in the table by a table bushing or master bushing, these slips fitting in a tapered opening and being caused to tightly grip the pipe so as to support the same.
25 In the conventional rotary table the drive bushing is supported by the master bushing and the twisting of the kelly tends to spread the master bushing causing wear thereon and on the inside of the rotary table. This wear results in
30 a poor fit between the slips and the tapered bore of the master bushing resulting in an imperfect contact between the slips and the drill pipe.

It is an object of my invention to provide a rotary machine of the general character referred to above in which wear on the table bushing or master bushing by reason of engagement of the drive bushing therewith is wholly eliminated.

It is also an object of my invention to provide a rotary machine in which the drive bushing and table bushing are independently supported in the table opening and are each independently driven by the table, and in which these two bushings are wholly out of contact with each other so that the drive bushing will not transmit any driving forces or weight to the table bushing.

It is a still further object of my invention to provide a combination including a rotary table, a drive bushing, and a table bushing in which the bushings are of special design in order that the features of my invention pointed out in the preceding paragraphs may be achieved when used with the standard type of rotary table.

It is also an object of my invention to provide a combination of the character pointed out heretofore in which the drive bushing is rotated by

upright driving shoulders formed within the table opening and is supported by a lateral supporting shoulder which engages a shoulder of the rotary table formed at the top of the table opening.

It is a still further object of my invention to provide a rotary machine and bushing combination in which the rotary table may employ the special bushings of my invention or, if desired, may employ the standard bushings now available on the market.

It is a still further object of my invention to provide a combination including the features and advantages of my invention and accomplishing the objects set forth heretofore in which the upper surface of the drive bushing is substantially flush with the upper surface of the table.

It is another object of my invention to provide a unique article of manufacture consisting of a drive bushing which is so designed that it may be employed with standard designs of rotary tables to enable the attainment of the objects, features, and advantages of my invention.

Other objects and advantages of my invention will be pointed out in the course of the following detailed description of three forms of my invention which have been chosen for the purpose of instructing those skilled in the art as to how my invention may be practiced. It should be understood, however, that my invention is not limited to the details of construction to be hereinafter described and illustrated in the accompanying drawings, but my invention should be construed to cover all modifications thereof which come within the spirit and scope of the preceding statement of invention and appended claims.

Referring to the drawings:

Fig. 1 is an elevational view partly in section showing one form of my invention.

Fig. 2 is a plan view of the table end of the rotary machine shown in Fig. 1.

Fig. 3 is a section taken on the line 3—3 of Fig. 2.

Fig. 4 is a section taken on the line 4—4 of Fig. 1.

Fig. 5 is a fragmentary section of a locking means for the drive bushing and is taken on the line 5—5 of Fig. 2.

Fig. 6 is a section taken on the line 6—6 of Fig. 5.

Fig. 7 is a detailed view showing the locking means for the table bushing and is taken on the line 7—7 of Fig. 2.

Fig. 8 is a fragmentary sectional view of the table end of the rotary machine showing the manner in which the table bushing supports slips which in turn support the drill pipe.

5 Fig. 9 is a fragmentary sectional view showing a second form of my invention.

Fig. 10 is a plan view of Fig. 9.

Fig. 11 is a fragmentary sectional view showing a third form of my invention.

10 Referring to the drawings in detail and particularly Figs. 1 to 7 inclusive, the numeral 11 represents a base on which a rotary table 12 is supported by means of a main bearing 14. The table 12 has a ring gear 15 secured to it 15 which is in engagement with a pinion 16, which pinion 16 is supported to a shaft 17 which may be rotated through the medium of a sprocket 18.

20 The table 12 has a top portion 20 having a top wall 21, and depending from the top portion 20 is a skirt 22 which is of general cylindrical shape and is surrounded by the main bearing 14. At the lower end of the skirt there may be, in accordance with standard practice, a hold-down bearing 23 which restrains the table 12 25 from vertical movement.

30 The table 12 has a table opening 24 which is concentric to the axis of rotation of the table and is divided into two sections, an upper shouldered section 26 and a lower cylindrical or skirt section 28. The upper shouldered section 26 is preferably of polygonal cross-section and has vertical walls 29 which constitute driving shoulders and has a lower lateral or horizontal wall 30 which constitutes a lower supporting shoulder.

35 The upper ends of the driving shoulders 29 terminate in the plane of the top wall 21, and surrounding the upper shouldered section 26 is an upper supporting shoulder 31 which is coextensive with and is in the same plane as the top wall 21 of the rotary table.

40 In Fig. 8 I have illustrated a table bushing or master bushing 37 which is positioned in the table opening 24. This table bushing 37 is preferably split into two halves 38 and 39 so that it 45 may be installed in the table opening while a drill pipe, such as indicated at 40, is extending through the table opening. This table bushing 37 has an upper shouldered portion 41 which corresponds in cross-sectional shape to the cross-sectional shape of the upper shouldered portion 50 26 of the table opening 24 and has a lower cylindrical portion 42. The shouldered portion 41 rests in the lower part of the upper shouldered section 26 and has upright driving shoulders 43 55 which engage the lower parts of the driving shoulders 29 whereby relative rotation between the table and table bushing 37 is prevented and whereby the table may be caused to drive the table bushing. The shouldered portion 41 of the 60 table bushing 37 also has lateral supporting shoulders 44 adapted to engage the lower supporting shoulders 30 of the table opening 24 in order to support the table bushing 37. The cylindrical portion 42 of the table bushing 37 has a 65 cylindrical wall 46 which may engage the cylindrical wall of the skirt portion 22 of the table 12. The table bushing provides an inner conical or tapered wall 47 which receives a plurality of pipe slips 48 which engage and support the drill pipe 40. There are preferably three slips which 70 are inserted into the table opening from the top thereof by workmen on the derrick floor and may be provided with suitable handles, not shown. The various interengaging supporting surfaces 75 are made concentric to the axis of rotation of the

table and are made complementary to each other in order that the drill pipe 40 will be concentrically supported and will be evenly and fully engaged by the teeth formed in the slips 48.

5 In Figs. 1 to 4 I illustrate my invention with a drive bushing or kelly bushing 50 in the position which it occupies when the kelly is being driven thereby. The drive bushing 50 of this form of my invention is preferably provided in two parts 51 and 52 which coengage along a diametral line 53. The drive bushing 50 has a central opening 54 of rectangular or other polygonal cross-section and is adapted to drivably engage a drive stem or kelly 55. The drive bushing 50 includes a shouldered portion 56 and a depending portion 57. The shouldered portion 56 is preferably of polygonal cross-section and corresponds in cross-sectional shape to the cross-sectional shape of the upper shouldered section 26 of the table opening 24. The shouldered portion 56 has vertical walls 59 which constitute driving shoulders and are adapted to engage the upper portions of the driving shoulders 29 of the upper shouldered section 26 of the table opening 24. Also provided as a part of the shouldered portion 56 or provided as extending from the upper part thereof is an upper outwardly projecting flange 60, as shown best in Figs. 2 and 3, which constitutes upper supporting shoulders which are adapted to engage the upper supporting shoulder 31 formed at the upper end of the upper shouldered section 26. The depending portion 57 projects downwardly into the conical opening provided by the table bushing 37 and is provided in order that the walls of the opening 54 may be relatively long so as to give an ample driving connection between the drive bushing and kelly.

30 When the parts are in driving position, as shown in Figs. 1, 2, and 3, the drive bushing 50 is supported within the table opening 24 and by the supporting shoulder 31 and is driven by the driving shoulders 29. At this time the slips 35 48 are not in use and have been removed from the master bushing 37 so that the lower part of the drive bushing may be accommodated in the conical opening 47.

45 The parts are so proportioned and designed that there is no contact whatsoever between the drive bushing 50 and the table bushing 37, and 50 these parts are separated by a small space 62 as well illustrated in Figs. 1 and 3. The table 12 therefore independently supports the drive bushing and the table bushing and independently drives both of these bushings. No driving force or weight is transmitted from the drive bushing 50 to the table bushing 37, as is obvious from an inspection of the drawings.

55 In order that the bushings may be locked in the table, suitable lock means is provided. The drive bushing 50 is locked in place by means of a lock means which includes a latch member 65 mounted on a rotatable shaft 66 which extends to the top wall 21 of the table and which, upon rotation, is movable from a position within a pocket 67 of the table, which position is illustrated by dotted lines 68, into a locking position which is shown by full lines in Figs. 5 and 6, and in which the end of the latch 65 extends into a recess 68 of the drive bushing 50. The table bushing is locked in place by a similar construction, as illustrated in Fig. 7, which includes a latch member 70 movable between latched and unlatched position by a rotatable shaft 71 on which the latch member is mounted, and which 75

is adapted to extend into a recess 72 of the table bushing 37 when in latched position. By inserting a suitable wrench into polygonal openings 73 formed in the upper ends of the rods 66 and 71 the latches 65 and 70 may be operated in order to lock or unlock the bushings with respect to the table.

In Figs. 9 and 10 I illustrate an alternative form of my invention in which the top wall 80 of the drive bushing 50 is in the same plane as the top wall 21 of the table. This is accomplished by providing a recess 82 at the upper end of the upper shouldered section 26 and by forming the upper supporting shoulders 31 at the bottom 15 of this recess 82. In this way the outwardly projecting shoulders 60 of the drive bushing 50 may rest in the recess 82 and lower faces 33 thereof may engage the shoulders 31. This form of the invention may be employed where the operator prefers to have the top wall 80 of the drive bushing exactly flush with the top wall 21 of the rotary table.

In Fig. 11 I illustrate another form of drive bushing identified by the numeral 90, which type of bushing is intended to be supported at all times by the kelly 55. This type of drive bushing includes a one-piece body which has a cylindrical wall 91 which extends upward from the shouldered portion 56 and which cooperates with the remainder of the bushing to provide a central opening 92 in which kelly engaging means or blocks 93 are supported, these blocks being retained between the lower shoulder 94 and an upper retaining member 95 which is bolted to the upper end of the wall 91. When the kelly is moved upward the joint 97 at the lower end thereof will engage the drive bushing and lift it upwardly from the table opening. In this form of my invention it is not necessary to manually remove the drive bushing from place as in the other two forms of my invention.

In the use of any of the forms of my invention disclosed therein both the table and drive bushings are in place during the driving of the kelly. The table bushing 37 remains in place at all times ready for use. When it is desired to support the drill pipe, the kelly is pulled upward and the drive bushing is unlocked and removed. The slips, such as illustrated at 48, may then be inserted in place and drill pipe supported as desired. The table bushing is used only for supporting the slips which support the drill pipe, and in my invention the table bushing is not called upon to support or drive the drive bushing and no supporting or driving forces are transmitted from the drive bushing through the table bushing to the table. The table bushing and walls or shoulders engaging the same are not subjected to wear which would result if the table bushing supported and drove the drive bushing, and therefore these interengaging shoulders or surfaces will remain in good condition and alignment over a long period of time and will support the slips 48 in a concentric and aligned position over long periods of use. If it is necessary to remove large objects through the rotary table, the entire table opening may be made accessible by first unlocking the table bushing and then removing it from the table opening 24.

My invention employs a standard table with a standard table opening in order that the advantages of my invention may be obtained in rotary machines now in use merely by obtaining and using the special bushings of my invention.

The design of the drive bushing whereby this

drive bushing may be supported in the opening of a standard rotary table and in such a position that it will not be in driving contact or supporting contact with the table bushing is an important consideration of my invention.

I understand that various modifications and alterations may be made in my invention without departing from the spirit and scope thereof, and I therefore wish my invention to be broadly construed in accordance with the statement of invention and appended claims.

I claim as my invention:

1. In a rotary machine of the class described, the combination of: a base; a rotary table supported by said base, said table having a table opening which includes an upper shouldered section having a driving shoulder, an upper supporting shoulder at the upper part of said driving shoulder, said upper supporting shoulder being below the top wall of said table, and a lower supporting shoulder at the lower part of said driving shoulder; a table bushing in said opening having a shouldered portion positioned in the lower part of said upper shouldered section, said shouldered portion having a driving shoulder engageable with said driving shoulder of said upper shouldered section and having a supporting shoulder engageable with said lower supporting shoulder; and a drive bushing for driving a kelly positioned in said table opening having a shouldered portion positioned in said upper shouldered section, said shouldered portion having a driving shoulder and a supporting shoulder engageable respectively with said driving shoulder and said upper supporting shoulder of said table opening, said table bushing and said drive bushing being independently supported by said table and said drive bushing transmitting no driving forces or weight to said table bushing.

2. In a rotary machine of the class described, the combination of: a base; a rotary table supported by said base, said table having a table opening which includes an upper shouldered section having a driving shoulder, an upper supporting shoulder at the upper part of said driving shoulder, and a lower supporting shoulder at the lower part of said driving shoulder; a table bushing in said opening having a shouldered portion positioned in the lower part of said upper shouldered section, said shouldered portion having a driving shoulder engageable with said driving shoulder of said upper shouldered section and having a supporting shoulder engageable with said lower supporting shoulder; and a drive bushing for driving a kelly positioned in said table opening having a shouldered portion positioned in said upper shouldered section, said shouldered portion having a driving shoulder and a supporting shoulder engageable respectively with said driving shoulder and said upper supporting shoulder of said table opening, said table bushing and said drive bushing being independently supported by said table and said drive bushing transmitting no driving forces or weight to said table bushing.

3. In a rotary machine of the class described, the combination of: a base; a rotary table supported by said base, said table having a table opening which includes an upper shouldered section having a driving shoulder, an upper supporting shoulder at the upper part of said driving shoulder, and a lower supporting shoulder at the lower part of said driving shoulder; a table bushing in said opening having a shouldered portion positioned in the lower part of said upper shoul-

shoulder which projects outwardly therefrom and a supporting shoulder engageable respectively with said driving shoulder and said upper supporting shoulder of said table opening, said table bushing and said drive bushing being independently supported by said table and said drive bushing transmitting no driving forces or weight to said table bushing. 5

6. In a rotary machine of the class described, the combination of: a base; a rotary table supported by said base, said table having a table opening which includes an upper shouldered section having a driving shoulder, an upper supporting shoulder at the upper part of said driving shoulder, and a lower supporting shoulder at the lower part of said driving shoulder; a table bushing in said opening having a shouldered portion positioned in the lower part of said upper shouldered section, said shouldered portion having a driving shoulder engageable with said driving shoulder of said upper shouldered section and having a supporting shoulder engageable with said lower supporting shoulder; and a drive bushing for driving a kelly positioned in said table opening having a shouldered portion positioned in said upper shouldered section, said shouldered portion having a driving shoulder which projects outwardly therefrom and a supporting shoulder engageable respectively with said driving shoulder and said upper supporting shoulder of said table opening, said table bushing and said drive bushing being independently supported by said table and said drive bushing transmitting no driving forces or weight to said table bushing.

7. In a rotary machine of the class described, the combination of: a base; a rotary table supported by said base, said table having a table opening which includes an upper shouldered section having a driving shoulder, an upper supporting shoulder at the upper part of said driving shoulder, and a lower supporting shoulder at the lower part of said driving shoulder; a table bushing in said opening having a shouldered portion positioned in the lower part of said upper shouldered section, said shouldered portion having a driving shoulder engageable with said driving shoulder of said upper shouldered section and having a supporting shoulder engageable with said lower supporting shoulder; and a drive bushing for driving a kelly positioned in said table opening having a shouldered portion positioned in said upper shouldered section, said shouldered portion having a driving shoulder which projects outwardly therefrom near the upper part of said shouldered portion of said drive bushing and a supporting shoulder engageable respectively with said driving shoulder and said upper supporting shoulder of said table opening, said table bushing and said drive bushing being independently supported by said table and said drive bushing transmitting no driving forces or weight to said table bushing. 40 45 50 55 60
